UNITED STATES PATENT OFFICE.

GEORGE R. GUILD, OF NEW YORK, N. Y., ASSIGNOR, BY MESNE ASSIGNMENTS, TO RAND KARDEX BUREAU, INC., OF TONAWANDA, NEW YORK.

INDEX DEVICE.

Application filed December 20, 1924. Serial No. 757,187.

This invention relates to card indexes and more particularly to card indexes of the type in which a plurality of cards are mounted in an upright frame in overlapping relationship so that the lower margins of the cards are visible and so that the cards may be swung apart to display the data on the overlapping portions, and objects of this invention are to provide an index device having the new and improved features of construction and arrangement hereinafter described.

The invention is illustrated in one of its preferred forms in the accompanying drawings, in which:

Fig. 1 is a front view of an index unit constructed in accordance with the present invention;

Fig. 2 is a fragmentary front view of the index unit with the "on order" slip removed;

Fig. 3 is an enlarged section substantially on the line 3—3 of Fig. 1; and

Fig. 4 is a front view of the order slip.

In the illustrated embodiment of the invention the index unit comprises a holder 1 of cardboard or relatively stiff paper on the upper margin of which is flexibly connected a supporting rail 2 which projects beyond the sides of the holder and is adapted to extend into channels in a suitable supporting frame for holding the unit in place. Detachably connected to the holder 1 is a sheet 3 which may be of relatively flexible paper or other suitable material and is preferably smaller than the holder.

Enclosing the lower margins of the holder 1 and sheet 3 and connected to the holder as by staples 4 is a sheath 5 of transparent sheet material such as sheet celluloid which may be formed of a sheet of such material folded upon itself along one longitudinal margin to form front and rear walls which are yieldingly urged toward each other owing to the resiliency of the material. The corners of the sheet 3 remote from the sheath 5 extend through diagonal slits 6 in the holder 1 so that in this manner the sheet is properly held in position relatively to the holder, but may be readily detached therefrom when occasion arises.

Formed in the sheet 3, preferably adjacent to and extending in substantially parallel relationship to the free edge of the front of the sheath 5 is an opening or slit 7.

Also provided in the sheet 3 is an aperture 8 which is preferably positioned between the slit 7 and the lower margin of the sheet to be visible through the sheath 5. As indicated in Fig. 1 a slip 9 is formed with cut-away or bevelled lower edges 10 to permit it to readily be inserted through the slit 7 and extend between the sheet 3 and holder 1. On the slip 9 adjacent the lower margin thereof and arranged to show through the aperture 8 when the slip is in place is an area 11 which may be colored differently from the holder 1. It will readily be understood that when the slip is in place in the index unit this will be visibly indicated through the aperture 8 in the sheet 3 by means of a portion of the colored area 11 showing therethrough, and when removed from the unit this also will be indicated by a different color showing through the aperture. Such signal is particularly advantageous when a number of units are arranged in spaced overlapping relationship, because it becomes unnecessary to swing one unit relatively to adjacent units to determine the presence or absence of the slip 9.

An index unit as above described may be used in a variety of situations but is shown as adapted for keeping a detailed account of sales made from a certain stock so that at a glance a user of the index may determine the sales progress in different lines so that a new stock may be ordered in proper time and the sales policy adjusted according to the selling ability of the slow-moving or weak lines. For this purpose a suitably graduated scale 12 may be provided adjacent the lower margin of the sheet 3 to be visible through the transparent sheath 5 and slidable between the front wall of the sheath and the sheet 3 may be positioned a pair of signals 13 and 14 respectively which are preferably differently colored in order to be readily distinguishable. The signal 14 may indicate the amount of stock on hand and in this instance as shown in Fig. 1 this indicates on the scale that there were 18 articles of a certain character initially in stock and the signal 13 serves to indicate the number of articles which have been sold from the initial stock which in the present case is 8. The difference between the two indications, i. e. between 18 and 8 or 10 indicates the number of articles remaining from the initial stock which are

waiting to be sold. The sheet 3 may be suitably ruled and inscribed to receive contemporaneous entries so that from day to day the sales may be recorded for future reference to enable the establishment more intelligently to regulate their buying and selling policy in the future.

When the signal 13 has approached the signal 14 to such an extent to reach the minimum order limit it is then necessary to replenish the stock and the slip 9 may be employed to indicate that additional merchandise has been ordered. For this purpose the slip 9 may have such indicia as "Date of order," "Order No.," "Quantity" etc., and after having been filled out by the buyer it may be inserted in place in the index unit, the presence therein being indicated as above pointed out by the different color showing through the aperture 8 so that this will be indicated readily even to the most casual observer. As soon as the order is filled the signal 14 is moved accordingly and the slip 9 removed from the unit, the absence of the slip also being indicated by a different color showing through the aperture 8.

Although I have shown and described a device which at the present time is believed to be the best form, it will be understood that numerous changes in details of construction, arrangement and selection of material may be made without departing from the spirit of the invention, especially as defined by the appended claims. It is further to be understood that I do not wish to limit the invention to the use hereinbefore described as it may be used to advantage in numerous other situations. It is to be understood that the term colors throughout is used in a broad sense to connote contrasting hues or shades whether actually colored or black, white, gray, etc.

I claim:

1. An index device comprising a sheet having a slit adjacent and extending substantially parallel to the lower margin thereof, and having an aperture between

said slit and said lower margin, and a slip extending through said slit and having a colored area visible through said aperture, thereby to indicate the presence of said slip.

2. An index device comprising a holder, a sheath of transparent sheet material enclosing a margin of said holder to form a pocket therewith, a sheet in said pocket having an opening adjacent to said sheath, and a slip having a portion extending into said pocket between said sheet and holder with a portion projecting through said opening.

3. An index device comprising a holder, a sheath of transparent sheet material enclosing a margin of said holder to form a pocket therewith, a sheet in said pocket having a slit adjacent said sheath and extending substantially longitudinally thereof, and a slip having a portion extending through said slit between said holder and sheet and another portion extending outside of said slit.

4. An index device comprising a holder, a sheath of transparent sheet material enclosing a margin of said holder to form a pocket therewith, a sheet extending into said pocket and having an opening and also having an aperture in the region of said sheath, a slip extending through said opening between said holder and sheet, and visible through said aperture to indicate the presence or absence of the slip.

5. An index device comprising a holder, a sheath of transparent sheet material enclosing the lower margin of said holder to form a pocket therewith, a removable sheet in said pocket, said sheet having a slit extending alongside said sheath and also having an aperture adjacent the lower margin thereof, a slip extending through said slit between said holder and sheet, and a colored area on said slip arranged to be visible through said aperture thereby to indicate the presence of said slip.

Signed by me at New York, N. Y., this 15th day of December 1924.

GEORGE R. GUILD.
